UNITED STATES PATENT OFFICE.

BAPTISTE MARTIAL PERICAUD, OF LIMOGES, FRANCE.

HEEL-SEAT-CUTTING MACHINE.

Application filed December 7, 1925, Serial No. 73,543, and in France December 9, 1924.

The object of my invention is a machine which allows part of the manufacture of shoes with Louis heels to be made with much less handicraft than has been used up till now. This machine is used before the heels are fixed on the shoe for cutting the rear part of the soles.

I will first state how the sole of a shoe with Louis heels is made. This sole 1 (Fig. 10) comprises at its rear part two tongues, the former of which passes in the finished shoe between the heel and the shoe, the other being folded over and stuck to the front of the heel so as to reinforce the means for securing the heel to the shoe. Up till now all these tongues have been prepared by hand: the rear part of the sole having been cleft previously, the front of the sole is first secured to the lower part of the shoe and the 20 tongues 2 and 3 are then cut.

The machine according to my invention will cut these parts automatically.

Before describing the principal features of the machine, I will begin by showing the 25 operations it has to carry out. These operations are shown diagrammatically on Figs. 2_a, 2_b, 2_c and 3_a, 3_b, 3_c, the Figs. 2_a and 3_a being side views, the Figs. 2_b and 3_b plan views and Figs. 2_c and 3_c detail views on an enlarged 30 scale.

The first stage (Fig. 2) consists in cutting the tongue 2 which is to be placed between the heel and the shoe; this operation consisting in bringing the shoe 4 with its sole 1 under a press-knife 5. The two strips 2' and 3' are shown before cutting. The strip 2' is folded over the bearing plate 6, the strip 3' being held forward. The tongue 2 which is obtained by this cutting operation will 40 have the shape of the hollowed out portion 7 of the press-knife 5. In view of the second stage of the operation (Fig. 2) which consists in cutting the tongue 3 out of the strip 3', a second press-knife 8 is used the hollowed out portion of which has the exact 45 shape of the front part of the heel and is much larger than the hollowed out portion 7 of the press-knife 5. But if the press-knife were to cut the strip 3' whilst the tongue 2 is still resting on the plate 6, the cutting would not be properly done as the strip 3' would not lie quite flat. Therefore 50 the plate 6 is replaced by a hollowed out auxiliary plate 10 provided with a supporting plate 6', the shape of the hollowed out portion of the plate 10 being exactly the

same as that of the press-knife 5. The cut tongue 2 fits exactly therein, whereby on one hand the strip 3' can be perfectly flat and the shoe on the other hand is perfectly seated, this being provided by the exact correspondency between the tongue 2 and the hollowed out portion of the auxiliary plate 10.

The machine for carrying out these operations comprises a frame wherein the press-knife is adapted to move to and fro. A movable vise supporting the shoe allows it to be brought under the press-knife and allows it to be moved vertically with reference thereto. Finally, a bearing plate is secured to the frame so as to support the leather which is being cut.

In order to carry out the first stage of the operations the machine should comprise 75 a device allowing the position of the shoe with reference to the press-knife to be adjusted accurately, this adjustment varying with the size of the shoes. This device is constituted preferably by a stop which has 80 the exact shape of the rear part of the shoe and is adapted to be moved by a screw which has only a longitudinal motion produced by a controlling nut. This screw is provided with a vernier cooperating with a scale provided on the frame whereby the shoe can be very accurately put in place.

For the second operation the machine is provided with an auxiliary plate the hollowed out portion of which is the same as 90 that of the press-knife which has served for the first operation; this plate can be secured to a supporting plate and holds the tongue cut during the first operation whilst the second is being formed.

Evidently if the number of shoes to work upon is great enough, it will be of advantage to use two different machines for carrying out the two operations; the use of two machines does not widen to any degree the 100 scope of the invention.

A machine according to my invention is described hereinbelow by way of example and shown on appended drawings wherein;

Figs. 1, 2_a, 2_b, 2_c, 3_a, 3_b, 3_c are the explanatory diagrams described already.

Figs. 4 and 5 are two vertical views perpendicular one with reference to the other;

Fig. 6 is a detail of Fig. 4 at an enlarged scale, Figure 4 showing the machine ready for the first operation and Figure 6 for the second.

In the frame 12 a shaft 13 is adapted to rotate. It bears the control lever 14 and the eccentric parts 15 which actuate through the small rod 16 a piston 17 which bears the 5 press knife 5 or 8 shown on Figs. 2 and 3. The piston 17 is guided in the sleeve 18. Its deflection towards the right or the left is prevented by a stud (not shown) sliding in a groove provided in the frame 12.

10 The frame shows a slide 19 wherein the sole 20 of the vise which supports the shoe is adapted to move. To this sole is secured a threaded screw 21 cooperating with the threaded sleeve 22 which allows the support 15 23 of the shoe to be raised or lowered. This support is independent of the sleeve and simply rests on it so as not to rotate along with it. The movement of the sole is stopped by a stop plate 24. It can be secured in its correct position by means of a lever 25, the eccentric pivot of which bears against a blocking part 28.

The accuracy of the position of the shoe for the first operation is ensured by the 25 stop 29 which is hollowed out so as to show the exact shape of the seat or rear part of the shoe. This stop is secured to the end of a threaded rod 30 which passes through a controlling nut 31 held by the frame so as 30 to be unable to move longitudinally along the rod 30. The latter on the other hand, is provided with a rear part 32 having a 35 square section adapted to move in a square hole, whereby the threaded rod 30 is prevented from rotating. By actuating the nut 31 the stop 29 is caused to move forward or rearward. A vernier plate 33 is secured to the rod 30 and moves in front of the stationary scale 34 disposed on the frame, 40 thereby enabling a correct placing of the stop according to the size of the shoe. For the second operation the auxiliary plate 10 (Fig. 6) is secured on a supporting plate. As stated hereinbefore this hollowed out 45 plate allows the accurate placing of the shoe with reference to the press-knife.

The form of execution which has been described has only been given by way of example and any constructional modifications can be brought to it without extending the 50 scope of the invention. Thus for instance the plate 6 could instead of being secured to the frame of the machine be secured to the press-knife holder with the interposition of springs. 55

Evidently if as already stated, two machines are used, the one intended for the second operation need not be provided with an adjustable stop 29 because in this case the shoe can be accurately put in place by 60 means of the tongue punched during the first operation.

What I claim is:

1. In a heel seat fitting machine, a frame, a shoe support carried thereby, a press knife 65 mounted in the frame for movement towards and from a shoe on said support, a bearing plate carried by the frame for supporting a flap on the rear portion of the sole of the supported shoe which has been previously 70 cut in such a manner as to adapt it to be inserted between the shoe and a heel to be attached thereto, and a second plate secured to the bearing plate for supporting a second flap on the rear portion of said sole 75 and having a hollowed out portion the side edges of which correspond to the side edges of the first mentioned previously cut flap.

2. In a machine as claimed in claim 1, the combination of a stop adapted to fit against the seat of the shoe, a screw secured to said stop, a nut cooperating with the screw and adapted to move it longitudinally together with the stop, means whereby the screw is prevented from rotating, means whereby the 85 nut is prevented from moving longitudinally, a vernier borne by the screw, and a graduation borne by the frame in front of said vernier. 90

In testimony whereof I have affixed my signature.

BAPTISTE MARTIAL PERICAUD.
